UNITED STATES PATENT OFFICE.

CALVIN RUTSTRUM, OF MINNEAPOLIS, MINNESOTA.

SKATE-SHARPENER CLAMP.

1,420,756.

Specification of Letters Patent. Patented June 27, 1922.

Application filed April 1, 1920. Serial No. 370,554.

To all whom it may concern:

Be it known that I, CALVIN RUTSTRUM, a citizen of the United States, residing at Minneapolis, in the county of Hennepin and 5 State of Minnesota, have invented certain new and useful Improvements in Skate-Sharpener Clamps; and I do hereby declare the following to be a full, clear, and exact 10 description of the invention, such as will enable others skilled in the art to which it appertains to make and use the same.

My invention has for its object to provide an extremely simple and highly efficient skate sharpener clamp for rigidly holding a 15 pair of skates in respect to each other, while simultaneously sharpening the running edge thereof with a carborundum or other cutting stone. The improved clamp is intended for general use, but is especially adapted for 20 holding so-called tube skates permanently secured to skating shoes, and which shoes afford a support and clamp for the skates while the skates are being sharpened.

By the application of the improved clamp 25 to a pair of skates, the blades thereof are automatically brought into parallel arrangement in respect to each other in all directions and with their running edges in the same plane, so that by resting a cutting 30 stone on both of said running edges and rubbing the same thereover, the skates may be correctly sharpened. The clamp is portable with the pair of skates to which it is applied and is confined entirely between the 35 running edges of the skates and the shoe plates thereof.

To the above end, generally stated, the invention consists of the novel devices and combinations of devices hereinafter described and defined in the claims.

In the accompanying drawings, which illustrate the invention, like characters indicate like parts throughout the several views.

45 Referring to the drawings:—

Fig. 1 is a perspective view showing a pair of shoes to which is attached a pair of tube skates held by my improved clamp, and also showing, by means of broken lines, a cutting stone resting on the running edges of the skates in position to sharpen the same; and

50 Fig. 2 is a transverse section taken on the line 2—2 of Fig. 1 and further illustrating a support to which the clamp is secured.

The numeral 3 indicates a pair of so-

called tube skates secured to a pair of shoes 4, and the numerals 5 and 6 indicate, respectively, a table or other support to which the improved clamp is attached, and a cutting stone, preferably carborundum, with a coarse side and a fine side.

The improved clamp includes a bridge member 7 having integrally formed with its longitudinal edges a pair of upturned parallel fixed jaws 8 and a pair of co-operating movable jaws 9 applied to the outer faces of said fixed jaws. Both the fixed and movable jaws of each pair have, in their inner faces, longitudinally extended grooves or channels 10 arranged to receive the tubular backs of the skates 3, with the blades thereof extending between the upper longitudinal edges of said jaws. The bridge plate 7 is stiffened by transversely creasing or otherwise forming 75 therein reinforcing ribs 7' and it is important to note that said bridge plate is located at a point between the running edges and shoe plates of the skates.

A pair of thumb-nut-equipped draw-bolts 80 11 is extended through aligned holes in the jaws 8 and 9 for drawing said movable jaws toward the fixed jaws under a varying pressure. To prevent the fixed jaws 8 from bending or drawing toward each other, under the action of the draw-bolts 11, there is placed on each of said bolts a sleeve 12, the ends of which bear against the inner faces of said fixed jaws.

By reference to Fig. 1, it will be noted 90 that the clamp is applied to the skates between the cups or standards thereof, and by reference to Fig. 2, it will be noted that each jaw of the clamp has a two-point contact with the respective skate, and under the 95 drawing action of the bolts 11, the jaws 8 and 9 securely close on the tubular backs of the skates and, by the long engagement therewith, hold the skates against lateral or twisting movements. As the clamps close 100 on the skates, the blades thereof are automatically positioned so that they are parallel to each other in all directions and with their running edges in the same plane. With the skates thus securely held, the cutting 105 stone may be placed on the skate, as shown, first with its coarse side in contact with the running edge thereof, and rubbed back and forth thereon until said blades are in fairly good condition. The sharpening of the 110 blades may be finished by using the fine side of the stone.

If desired, the clamp may be secured to the support 5 by means of a thumb-nut equipped draw-bolt 13 inserted through aligned holes in the bridge member 7 and 5 said support, as shown in Fig. 5. Obviously, by loosening the thumb nuts on the draw-bolts 11, the movable jaws 9 may be separated from the fixed jaws 8 sufficiently to permit the tubular backs of the skates to be 10 placed between said jaws or removed therefrom. While the skates are being sharpened, the shoes always afford a support for the skates and clamp, whether the securing bolt 13 is used or not.

15 The term "blade" is herein used in a broad sense to include the tubular member to which it is secured.

20 In actual usage, the improved clamp has proved highly efficient for the purpose had in view.

What I claim is:—

1. A skate sharpener clamp comprising a pressed metal bridge plate having at its longitudinal edges integrally formed fixed jaws, 25 a pair of movable jaws, said fixed and movable jaws having co-operating semi-cylindrical seats each constructed and arranged to engage the tubes of tube skates at two circumferentially spaced points, and nut-equipped draw bolts for drawing the movable jaws toward the fixed jaws.

2. A skate sharpener clamp comprising a pressed metal bridge plate having its longitudinal edge portions bent into parallel 35 arrangement to afford a pair of fixed clamps having semi-cylindrical jaw portions, movable jaws outward of the fixed jaws for co-operation therewith, said jaws being constructed and arranged to engage the tubes of 40 tube skates at two circumferentially spaced points, and a pair of nut-equipped bolts extending through apertures in the fixed and movable jaws between the bridge plate and their semi-cylindrical portions for drawing 45 the movable jaws toward the fixed jaws.

3. A skate clamp adapted to be disposed between the heel and toe supports of a pair of tube skates comprising a base member and a pair of jaws upstanding at each side thereof, one of the jaws of each pair being fixed 50 relative to said member, the other jaw of each pair being movable in relation thereto, the said jaws being of semi-cylindrical formation and adapted to embrace the tube of 55 said skates and engage therewith at circumferentially spaced points, whereby the said

tube and skate can be adjusted angularly in said jaw so that the runner face thereof may be finished on a bevel.

4. A support adapted to hold a pair of 60 skates for sharpening comprising a base plate member of much shorter length than the skate runners, said base plate member being bent upwardly at each side thereof to form fixed jaws rigid therewith, a movable 65 jaw mounted for co-operation with each of said fixed jaws, means for closing and holding said jaws in clamping position, said jaws being constructed and arranged to continuously engage the sides of the skate runners 70 at a relatively short portion near the center thereof between the heel and toe supports thereon.

5. A support for holding a pair of skates 75 for sharpening, comprising a pair of spaced jaws, each of said jaws being of semi-circular shape in cross section and constructed and arranged to clamp the tube of tube skates at circumferentially spaced points.

6. A support for holding a pair of skates 80 in position for sharpening comprising a base plate member, said member being bent upwardly at each side to form a terminal movable semi-cylindrical fixed jaw, a movable semi-cylindrical jaw arranged for co-operation 85 with each of said fixed jaws, spaced bracing members extending between the upwardly bent portions of the plate which form the fixed jaws, said jaws being adapted to continuously engage the skate runners for 90 a considerable distance between the heel and toe supports thereof, said base member and said jaws being of the same length.

7. A support for holding a pair of skates 95 in position for sharpening comprising a plate base member adapted to be disposed between the heel and toe supports of the skate runners, jaws extending upwardly from the sides of said plate, movable jaws arranged to co-operate therewith, headed 100 bolts extending across said plate through said jaw portions, tightening nuts at one end of said bolts and spaced tubular members extending above said plate between the fixed jaws in which said bolts are disposed.

In testimony whereof I affix my signature in presence of two witnesses.

CALVIN RUTSTRUM.
